UNITED STATES PATENT OFFICE.

DORSEY F. ASBURY, OF WASHINGTON, DISTRICT OF COLUMBIA.

BREECH MECHANISM.

1,415,912.

Specification of Letters Patent. Patented May 16, 1922.

Application filed July 13, 1920. Serial No. 395,869.

To all whom it may concern:

Be it known that I, DORSEY F. ASBURY, a citizen of the United States, and resident of Washington, in the District of Columbia, have invented certain new and useful Improvements in Breech Mechanisms, of which the following is a specification.

My invention relates to breech mechanisms and particularly those wherein rotation of the breech plug is necessary to effect locking and unlocking thereof.

The principal objects of my invention are to provide operating means which is connected to the breech plug at diametrically opposite points; to provide a breech mechanism which embodies only one reactionary acting bearing; to operate the breech plug by a mechanism having only rotary bearings which partake of very little rotary movement during such operation; to retain in my improved mechanism the method of hand lever operation disclosed in U. S. Patent 1,020,849; to simplify the carrier construction by providing a mechanism which is attached to the carrier and plug by detachable pivot pins at points easily accessible; to apply the operating force through two levers one of which compounds the force of the other; to so arrange the levers that any force emanating from the plug when the latter is locked is ineffective to move the mechanism; to divide the fore and aft travel of the plug due to the lead of the plug and screw box threads with respect to the axis of the bearing which is stationary with respect to the carrier, to reduce the theoretical error in both bearings of the actuating lever during operation to a minimum; to enable the plug and mechanism levers to be disassembled while the plug is in any rotary position or the mechanism is in any position of swing; to utilize the pivot pins of the plug operating member to carry the plug rotating roller and to hold the plug to the carrier; to utilize a single boss on the plug to connect the plug rotating roller and plug operating member; to rotate the plug through the instrumentality of two levers one of which generates in its movement a portion of a conical surface and the other a portion of the base of a cone including the conical surface generated by the first named lever; to provide a breech mechanism in which the necessity of machining the parts is eliminated to a large extent and the cost of manufacture thereby greatly reduced; to provide

a breech mechanism embodying an operating toggle effective immediately upon any slight movement of the hand lever; to provide a breech mechanism in which all connected parts are visible and accessible for oiling and disassembling; and to produce a mechanism in which absolute alinement of incorporated bearings is not required in manufacture.

In the drawings chosen to illustrate my invention the scope whereof is set forth in the claims:

Fig. 1 is a rear elevation of a gun provided with a breech mechanism constructed in accordance with my invention with the mechanism locked;

Fig. 2, a side elevation of the breech end of a gun provided with my breech mechanism, the latter being locked and the actuating handle or arm being also shown in dotted lines in the position it would occupy when full unlocking rotation has been imparted to the breech plug;

Fig. 3, a plan view of my improved breech mechanism with the parts in the position they would occupy when the breech plug is partially rotated toward unlocked position;

Fig. 4, a view similar to Fig. 2 with the carrier swung to full open position; and

Fig. 5, a section on the line 5—5 of Fig. 1. Referring to the drawings 10 indicates the gun, 11 the hinged carrier provided with the usual spindle 12 on which is slidably and rotatably mounted the breech plug 13. This plug is desirably of the threaded type shown in U. S. Patent 1,020,849 and coacts in the well known manner with an internally threaded screw box 14 suitably mounted in the breech end of the gun. The threads of the plug and screw box in this instance have a predetermined lead so that the plug in locking and unlocking has a slight fore and aft movement on the spindle 12, but it will be observed that my invention is equally applicable to breech structures wherein the threads of the plug and screw box have no lead.

My improved mechanism for effecting locking and unlocking rotation of the plug 13 comprises an actuating arm or lever 15 which is pivotally mounted on the carrier 11 through the instrumentality of a detachable pivot pin 16. The position of the pivotal axis of the arm 15 is such that a continuation thereof will intersect the axis of the plug 13. Suitably provided on the rear

face of the plug 13 are diametrically opposite pairs of bosses 17 and 18. The pairs of bosses 17 and 18 detachably support respectively pivot pins 19 and 20 having a common axis which intersects the axis of the plug 13. The mechanism further embodies a plug operating member 21 one end of which has a rotatable and non-slidable bearing connection with the arm 15 at 15' while the other end is forked to form arms 22 and 23 which are pivotally engaged on the pins 19 and 20 respectively. The position of the member 21 is such that its axis intersects the axis of the plug at 15 right angles and in the case of a plug having threads with no lead said axis of the plug operating member also intersects the pivotal axis of the arm 15 in the axis of the plug.

20 However, where the plug and screw box have lead threads, as in the present instance, the plug of necessity has slight though hardly appreciable fore and aft movements on the carrier and in order to 25 permit these slight movements of the plug without interference with the operation of the other parts of the mechanism I utilize an allowable tolerance of manufacture in constructing the parts, which tolerance is 30 reduced to substantially one-half by arranging the parts so that the point of intersection of the pivot axis of the actuating lever 15 with the axis of the plug is disposed to the rear of the point of intersecting 35 section of the axis of the plug operating member with the axis of the plug when the latter is locked and forward of said point when the plug is unlocked.

In order to hold the plug 13 to the carrier I extend the inner ends of the pins 40 19 and 20 respectively into grooves 24 and 25 provided in the carrier and rotatably engage the ends of said pins in bearing blocks 26 and 27 respectively which slide snugly 45 in said grooves during rotation of the plug.

I construct these grooves 24 and 25 with or without lead depending on whether the plug and screw box threads are constructed with or without lead.

50 In the form of my invention illustrated I utilize the energy stored up in the mechanism while swinging it into the breech to initiate a locking rotation of the plug 13 and also utilize unlocking rotation of the 55 plug to initiate opening swing of the carrier 11. To this end I rotatably mount on the pin 20 a roller 28 which coacts with a cam 29 fixed on the gun to produce the results just stated.

60 In respect to the assembly of the mechanism it will be observed that the pin 20 performs the triple function of securing the operating member 21 to the plug; holding the plug to the carrier, and forming a 65 spindle support for the roller 28 while the

pin 19 performs the dual function of securing the operating member to the plug and holding the plug to the carrier.

I claim:

1. In a breech mechanism, a rotatable 70 plug, an actuating lever, a plug operating member, a bearing connection between one end of the member and plug, and a bearing connection between the other end of the member and lever, said last named bearing connection having its axis disposed longitudinally of the member.

2. In a breech mechanism, a rotatable 75 plug, an actuating lever, a plug operating member, a bearing connection between one end of the member and plug, and a direct bearing connection between the other end of the member and a part fixed relatively to the lever, the axes of said bearing connections being disposed at right angles to each other and in the same plane.

3. In a breech mechanism, a rotatable 80 plug, an actuating lever, and a plug operating member connected to the plug by a pivot and directly connected to the lever by a 85 cylindrical bearing.

4. In a breech mechanism, a rotatable 90 plug, an actuating lever, and a plug operating member connected to the plug for pivotal movement only with respect thereto and directly connected to the lever by a cylindrical bearing.

5. In a breech mechanism, a rotatable 95 plug, an actuating lever, and a plug operating member, one end of which is connected to the lever and the other end pivotally connected to the plug, the axis of said pivotal connection being fixed with respect to the plug during all movements of the latter.

6. In a breech mechanism, a rotatable 100 plug, an actuating lever, and a plug operating member having bearing connections with the plug and lever respectively, the axis of the bearing connection between operating member and actuating lever being 105 always disposed in a plane including the axis of the plug.

7. In a breech mechanism, a rotatable 110 plug, a plug operating member connected to the plug by a pivot whose axis is at right 115 angles to and intersecting the axis of the plug.

8. In a breech mechanism, a carrier, a rotatable plug, a plug operating member pivoted to the plug, and an actuating lever 120 pivoted to the carrier and connected to the plug operating member, the axis of each of said pivots intersecting the axis of the plug at right angles.

9. In a breech mechanism, a carrier, a 125 rotatable plug, a plug operating member pivoted to the plug, and an actuating lever pivoted to the carrier and connected to the plug operating member, the axis of each of said pivots intersecting the axis of the plug 130

at right angles at substantially the same point.

10. In a breech mechanism, a carrier, a rotatable plug, a plug operating member having a rotary connection with the plug, an actuating lever having rotary connections with the carrier and plug operating member respectively, the axes of all of said rotary connections intersecting the axis of 10 the plug at substantially a common point.

11. In a breech mechanism, a carrier, a rotatable plug, a plug operating member having a rotary connection with the plug, and an actuating member operatively connected with the plug operating member, the axes of the latter and said rotary connection intersecting the axis of the plug at a common point.

12. In a gun, a carrier, a rotatable plug, 20 a pivot pin mounted on the plug, an operating member pivoted on said pin, a cam on the gun, and means on said pin for cooperation with said cam.

13. In a breech mechanism, a carrier, a rotatable plug, a pivot pin mounted on the plug, an operating member pivoted on said pin, a cam on the carrier, and means on said pin for cooperation with said cam.

14. In a gun, a carrier, a rotatable plug, 30 a pivot pin mounted on the plug, a plug operating member pivoted on said pin, a cam on the gun, and a roller on the pin for cooperation with said cam.

15. In a gun, a carrier, a rotatable plug, 35 a pivot pin mounted on the plug, a plug operating member pivoted on said pin, a cam on the gun, a cam on the carrier, and elements on the pin for cooperation with said cams respectively.

40 16. In a breech mechanism, a carrier having a spindle, a plug rotatably and slidably engaged on said spindle, a pivot pin mounted on the plug and having interlocking engagement with the carrier to hold the plug thereon, and an operating member pivoted 45 on the pin.

17. In a breech mechanism, a rotatable plug, a pivoted actuating lever, a plug op-

erating member having one end connected to the lever and its other end forked to form 50 arms, fixed with respect to the member and means fixed with respect to the plug and pivotally connecting said arms to the plug.

18. In a breech mechanism, a carrier having a spindle, a plug rotatably and slidably 55 mounted on said spindle, diametrically opposite pivot pins mounted on the plug, and interlocked with the carrier to hold the plug thereto, an actuating arm pivoted on the carrier, and a plug operating member having one end connected to the arm and its other end bifurcated and its furcations pivotally connected to the plug by said pivot pins respectively.

19. In a gun, the combination with a carrier and a rotatable plug having lead threads coacting with corresponding threads on the gun, of a plug operating member pivoted to the plug, and an actuating lever pivoted to the carrier, both of said pivot axes 70 intersecting the axis of the plug, the point of the actuating lever's pivot axis intersection with the axis of the plug being to the rear of the point of the plug operating member's axis intersection, when the plug is 75 locked and forward of said point when the plug is unlocked.

20. In a breech mechanism, a rotatable plug, and a plug operating member pivoted to the plug and moving with the plug's rotation, the pivotal movement of said member being first away from the plug and then toward the plug during each locking rotation of the plug and during each unlocking rotation of the plug. 85

21. In a breech mechanism, a carrier, a rotatable plug, an actuating lever pivoted on the carrier, a plug operating member pivotally connected to the plug and rotatably connected with the lever, the pivotal 90 axis of all of said connections being in the same plane when the plug is locked.
